UNITED STATES PATENT OFFICE.

WILLIAM A. VOLLMER, OF KENOSHA, WISCONSIN, ASSIGNOR TO SIMMONS COMPANY, OF NEW YORK, N. Y., A CORPORATION OF DELAWARE.

TIP.

Original application filed April 10, 1924, Serial No. 705,451. Divided and this application filed November 21, 1927. Serial No. 234,602.

This invention relates to tips or casters and sockets for mounting the same in or on the legs of chairs or other articles of furniture, and this application is a division of 5 my co-pending application for patent on tip, Serial No. 705,451, filed April 10, 1924.

The primary object of my invention is to provide a tip which is strong and durable in construction, attractive in appearance 10 when mounted on a chair leg or the like, and which may be cheaply and economically manufactured.

Other objects and advantages of the invention will be understood by reference to 15 the following specification and accompanying drawing in which I have illustrated a selected embodiment of my invention and in which drawing:

Fig. 1 is a side elevation of my improved 20 tip.

Fig. 2 is a section on the line 2—2 of Fig. 1, and

Fig. 3 is a bottom plan.

Referring now to the drawing, my improved tip structure includes a main mounting member or socket 10, a secondary mounting member or cushion holding member 11, and a cushion element 12. The main mounting member 10 preferably consists of a one 25 piece member having an end or bottom wall 13 from which a pair of arms 14 and 15 extend upwardly from oppositely disposed edge portions. The arms 14 and 15 are preferably bent inwardly as shown at 30 and 17 and provided with upturned end portions 18 and 19 which are adapted to abut when the mounting member is inserted into the recessed end of a leg member.

In Figs. 1 and 2 I have indicated in 40 dotted lines, a tubular metal leg member 20 in the lower end of which the mounting member is inserted. For limiting movement of the mounting member inwardly of the leg, I provide the bottom wall 13 with 45 seats 21 and 22 which are formed by marginal portions of the bottom wall 13 which project beyond adjacent edges of the arms 14 and 15. I also find it desirable to provide the arms 14 and 15 with inwardly bent 50 flanges or ears 23 and 24 which are effective to engage the inside of the leg member to thereby more firmly position the mounting member in the leg.

The bottom wall 13 is preferably aper-

tured as shown at 25 and provided with a 55 depending flange 26 around the aperture for receiving the secondary mounting member 11 which is preferably cup shaped, as best shown in Fig. 2.

The rim of the cup shaped mounting member 11 is bent outwardly to form an outwardly projecting rim flange 27 which is adapted to engage the end of the depending flange 26 to thereby position the cup shaped member 11 in the aperture of the mounting 65 member 10.

The rim flange 27 is preferably formed so as to provide a convex outwardly facing edge portion, as clearly shown in Fig. 2 for the purpose fully explained in my said co-pending application for patent on tip, 70 Serial No. 705,451, and the cushion member 12 may be seated and locked in the cup shaped member also as fully explained in my said co-pending application. 75

In the above disclosed embodiment of my invention I have illustrated a mounting member particularly adapted for use with rectangular tubular metal chair legs, and also more particularly adapted for use with 80 an inclined chair leg such as the rear legs of many chairs.

It will be readily understood that my improved tip structure may be used and manufactured with equal facility for legs which are not disposed at an angle to the floor, as well as for wooden legs provided with a recess in their lower ends. I am aware that many changes in the form, construction and proportion of parts may be made without departing from the spirit of the invention, the scope of which should be determined by reference to the following claims, which should be construed as broadly as possible, consistent with the state of the art. 85 90 95

I claim as my invention:

1. A tip for a chair leg or the like comprising a rectangular metal tube, said tip comprising a one-piece member having a substantially rectangular bottom wall provided with means adapted to engage a floor or other support without scratching or marring the same, and a plurality of flat arms integral with said bottom wall, extending upwardly from opposite edge portions 100 thereof, for entering said tube and frictionally engaging the inside of a pair of opposite walls, the upper ends of said arms be-

ing bent towards and abutting against each other so as to resiliently maintain the arms in spaced relation, thereby effecting tight frictional engagement between the arms and 5 walls, said arms being provided with ears projecting from the edges of the arms, bent to substantially right angles relative to the latter and adapted to engage the inside of the other opposite walls of said tube, and 10 marginal portions of said bottom wall intermediate adjacent edges of adjacent arms projecting laterally outwardly to serve as supports for portions of the lower end of the leg.

15 2. A tip for a chair leg or the like having a recess in its lower end, said tip comprising a one-piece member having a bottom wall provided with means adapted to engage a floor or other support without 20 scratching or marring the same and a pair of arms integral with said bottom wall, extending upwardly from opposite edge portions thereof, said arms being disposed substantially parallel to each other, inclined 25 relative to said bottom wall and adapted to enter the recess in said leg for frictionally engaging the inside of the wall of the recess, the upper ends of said arms being bent towards and abutting against each other so 30 as to resiliently maintain the arms in spaced relation thereby effecting tight frictional engagement between the arms and wall, the oppositely disposed marginal portions of 35 said bottom wall intermediate the upwardly extending arms projecting laterally outwardly to serve as supports for portions of the lower end of the leg.

3. In combination, a cushioned tip comprising a one-piece mounting member including a bottom wall having an opening 40 therein, a pair of arms integral with said bottom wall and extending upwardly from oppositely disposed edge portions of the bottom wall for entering a hollow leg and frictionally engaging the inside of the wall of 45 said hollow leg, oppositely disposed marginal portions of said bottom wall intermediate adjacent edges of said upwardly extending arms projecting laterally outwardly to serve as supports for portions of the adjacent end of the leg, a cushion member, and means for mounting said cushion 50

member on said bottom wall comprising a cup-shaped member snugly fitting the opening in said bottom wall and adapted to receive 55 said cushion.

4. In combination, a cushioned tip comprising a one-piece mounting member including a bottom wall having an opening therein, a pair of arms integral with said bottom wall and extending upwardly from oppositely disposed edge portions of the bottom wall for entering a hollow leg and frictionally engaging the inside of the wall of 60 said hollow leg, oppositely disposed marginal portions of said bottom wall intermediate adjacent edges of said upwardly extending arms projecting laterally outwardly to serve as supports for portions of the adjacent end of the leg, a cushion member, 65 means for mounting said cushion member on said bottom wall comprising a cup-shaped member snugly fitting the opening in said bottom wall and adapted to receive said cushion, and a laterally outwardly projecting rim flange on said cup-shaped member for engaging a portion of the bottom wall around said opening to position the cup-shaped member in said opening.

5. In combination, a cushioned tip comprising a one-piece mounting member including a bottom wall having an opening therein, a pair of arms integral with said bottom wall and extending upwardly from oppositely disposed edge portions of the bottom wall for entering a hollow leg and frictionally engaging the inside of the wall of 70 said hollow leg, the upper ends of said arms being bent towards and abutting against each other so as to resiliently maintain the arms 75 in spaced relation, thereby effecting tight frictional engagement between the arms and wall, oppositely disposed marginal portions of 80 said bottom wall intermediate adjacent edges of said upwardly extending arms projecting laterally outwardly to serve as supports for portions of the adjacent end of the leg, and means for mounting said cushion member on said bottom wall comprising a 85 cup-shaped member snugly fitting the opening in said bottom wall and adapted to receive said cushion.

WILLIAM A. VOLLMER.
